D DESIGN

J. B.

BONNET AND HAT HOLDER

18,379.

UNITED STATES PATENT OFFICE.

JAMES BENJAMIN CLIFFORD, OF SAN FRANCISCO, CALIFORNIA.

DESIGN FOR A BONNET AND MILLINERY STAND.

SPECIFICATION forming part of Design No. 18,379, dated June 12, 1888.

Application filed March 20, 1888. Serial No. 267,902. Term of patent 7 years.

To all whom it may concern:

Be it known that I, JAMES BENJAMIN CLIFFORD, a citizen of the United States, residing at San Francisco, in the county of San Francisco and State of California, have invented and produced a new and original Design for Millinery, Bonnet, Hat, and Feather Stands, of which the following is a specification, reference being had to the accompanying photographs, forming part thereof.

The center figure is a full view and the two outside figures a side elevation of my newly-invented bonnet, hat, and feather stands, these three views being necessary to fully illustrate my design. Heretofore such designs have been

made with a circular or triangular foot and a circular head. In these the foot is a configuration of a double cross with the upright stand in the center, and having an octagon-shaped head.

20

I claim—

The design for a new millinery, bonnet, hat, and feather show-stand, having the appearance of bamboo, provided with an upright, a double cross for the foot, and an octagon-shaped 25 head or top, as shown and described.

JAMES BENJAMIN CLIFFORD.
